UNITED STATES PATENT OFFICE.

ROY F. WHALLEY, OF SAN JOSE, CALIFORNIA.

KEY-REMOVING DEVICE.

1,294,582.

Specification of Letters Patent. Patented Feb. 18, 1919.

Application filed July 5, 1918. Serial No. 243,413.

To all whom it may concern:

Be it known that I, ROY F. WHALLEY, a citizen of the United States, and resident of San Jose, in the county of Santa Clara, California, have invented certain new and useful Improvements in Key-Removing Devices, of which the following is a specification.

My invention relates to a device used for 10 loosening and removing keys from fixed positions in the key-ways of shafts and the wheels or pulleys mounted thereon and held against rotation on said shafts by said keys.

In one of the customary methods of re- 15 moving keys, a wedge is used that bears against one corner of the key head and against the side of the wheel held by the key. This method causes mutilation of the key head because of the angular bearing of the wedge or key-drift against the same, and is unsatisfactory because the said key-drift binds against the more or less roughened side of the wheel. Also in using a method 20 of this kind, if the key projects beyond the end of the shaft it is easily bent because no support is provided for the back thereof, and in either case the key-drift has to be held in position by hand while driving.

It is, therefore, one object of my invention 25 to provide a device of the character indicated which causes the key-drift to assume a square bearing against the key head, thereby preventing the mutilation of said head, and to provide a smooth surface for the said 30 key-drift to operate against, thereby preventing marring of the key-drift in driving and also facilitating its removal.

Another object of my invention is to 35 provide a device of the character indicated 40 that will pull the key without binding the same in the key-way. Still another object is to provide a device of the character indicated in which the key-drift is automatically and properly positioned and held. 45 Still another object is to provide a device of such a nature that the key-drift will be so held as to contact with the key head only, thereby preventing the roughening or injuring of the key proper.

Other objects are to provide a device for 50 the purpose stated that will embody the above mentioned characteristics and that will be strong, simple and easily positioned, utilized and removed.

Other objects and advantages will appear

in the following description and accompanying drawing which are intended to cover one embodiment of my invention only. I do not, therefore, wish to confine my invention to the specific form and construction and combination shown and described, but to include all changes that may be made within the scope of the appended claims. 60

In the drawings:—

Figure 1 is a perspective illustration of 65 the device without the key-drift used therewith.

Fig. 2 is a plan view of the device in position to start a closely driven key.

Fig. 3 is a plan view of the device in position to move a key partly removed by the device when used as shown in Fig. 2. 70

Fig. 4 is a side elevation of the device when used to remove a key extending beyond the end of a shaft. 75

Fig. 5 is an end view of the device showing the chamfered corners of the end used in Fig. 4.

Fig. 6 is a plan view of the device having key-drift slots rectangular in form. 80

Fig. 7 is a perspective illustration of a key-drift having a bead formed thereon, part broken away.

Similar characters of reference indicate 85 similar parts throughout the several views.

Referring now more particularly to the drawing, 1 indicates a shaft having a key-way 2, a pulley 3 mounted thereon and locked in position by key 4, the numeral 5 indicating the head of said key 4. The body 90 of the device embodying my invention comprises a pair of parallelly spaced side members 6 and 7 joined near one end by a bridge 8 preferably formed integrally therewith and set a distance above the upper edges 95 thereof as indicated at 9. The short end is indicated by the bracket 10 and the longer end by the bracket 11. In sides 6 and 7 and in approximately the positions shown are formed slots 12 and 13 respectively, each 100 slot having beveled ends as indicated at 14 and 15, and 16 and 17 respectively for the purpose hereinafter set forth. The key-drift is indicated by numeral 18 and may be a metallic wedge of the thickness slightly 105 less than the width of slots 12 and 13. In the embodiment shown in Figs. 2 and 3 the key-drift 18 has tapering sides 19 and 20. As illustrated in these figures when the wheel 3 is a distance from the end of shaft 110

1 the device is first placed upon shaft 1 and bridging key 4 with end 10 abutting wheel 3. The key-drift 18 is now inserted through slots 12 and 13, side 20 engaging beveled ends 14 and 16 respectively, and side 19 engaging the head 5 of said key 4. The key-drift may now be driven through slots 12 and 13 until the key is so far removed that side 19 of key-drift 18 engages ends 15 and 17 of slots 12 and 13, whereupon the said key-drift 18 may be removed and the device reversed so that end 11 abuts pulley 3, thus bringing the head 5 of key 4 in the position shown in Fig. 3 so that the driving process 15 may be continued until the key is removed.

If the key projects over the end of the shaft 1 as shown in Fig. 4, then the device is positioned upon key 4 substantially as shown, and the inner edges of the ends 10 are chamfered as shown at 21 so that the upper surfaces of slots 12 and 13 may be positioned slightly lower than the outer surface of key 4 as shown in Fig. 4. The key-drift may now be driven in through slots 12 and 13 and the key removed as above described.

It will now be seen that by using this device the same key may be removed many times while being fitted without injury to any part thereof. The sloping ends 14—15 and 16—17 of slots 12 and 13 cause the key-drift to operate squarely upon head 5 of key 4. When the device is placed in position and the key-drift inserted ready for driving they lock with the key and shaft or with the key and shaft and pulley so that they do not have to be held during the driving operation. The thickness 22 is slightly greater than the exposed thickness of key 4 therefore key-drift 18 engages the bottoms of slots 12 and 13 and does not contact with the surface of key 4. The ends 14—15 and 16—17 of slots 12 and 13 always provide smooth surfaces for key-drift 18 to operate against. When the key projects beyond the end of shaft 1 as shown in Fig. 3 then the bridge 8 forms a support that prevents bending of the key.

It is understood of course, that slots 12 and 13 may have ends formed perpendicularly to their longer edges as shown in Fig. 6, or not, as practical application may require. Also since keys are provided with a channel as 23 in head 5, a bead as 24 may be provided upon the edge of key-drift 18 adapted to engage the said channel 23 thereby securing a solid bearing of said key-drift against the full thickness of the head 5. The key-drift holder may have a slot 60 as 25 formed therein to engage bead 24 on key-drift 18 if the position of the said key-drift is reversed for any reason.

I claim:—

1. A key removing device adapted to be used in conjunction with a shaft, wheel and

key in operative position with relation to each other, and comprising a pair of fixedly spaced side members adapted to straddle said key and engage said shaft and wheel and having slots formed therein to receive a key-drift, and a key-drift adapted to engage said slots and said key. 70

2. A key removing device adapted to be used in conjunction with a shaft, wheel and key in operative position with relation to each other, and comprising a pair of fixedly spaced side members adapted to straddle said key and engage said shaft and wheel and having slots formed therein to receive a key-drift, and a key-drift adapted to engage said slots and said key, said slots having beveled ends, and each end of one slot being in substantial alinement with the corresponding end of the other slot. 75 80

3. A key removing device adapted to be used in conjunction with a shaft, wheel and key in operative position with relation to each other, and comprising a pair of fixedly spaced side members adapted to straddle said key and engage said shaft and wheel and having slots formed therein to receive a key-drift, and a key-drift having a bead 85 formed on the edge thereof adapted to engage said slots and said key. 90

4. A key removing device adapted to be used in conjunction with a shaft, wheel and key in operative position with relation to each other, and comprising a pair of side members and a spacing bridge raised a distance above the connected portions of said side members, said side members being adapted to straddle said key and engage said shaft and wheel and having slots formed therein to receive a key-drift, and a key-drift adapted to engage said slots and 95 100 105 said key.

5. A key removing device adapted to be used in conjunction with a shaft, wheel and key in operative position with relation to each other, and comprising a pair of side members and a spacing bridge, said spacing bridge being shorter than said side members and positioned closer to one end thereof than the other, and said side members being adapted to straddle said key and engage said shaft and wheel and having slots formed therein to receive a key-drift, and a key-drift adapted to engage said slots and 110 115 said key.

6. A key removing device adapted to be used in conjunction with a shaft, wheel and key in operative position with relation to each other, and comprising a pair of side members and a spacing bridge, said spacing bridge being shorter than said side members and raised a distance above the connected portions thereof and positioned closer to one end thereof than the other, and said side members being adapted to straddle said key and engage said shaft and wheel and hav- 120 125 130

ing slots formed therein to receive a key-drift, and a key-drift adapted to engage said slots and said key.

7. A key removing device adapted to be used in conjunction with a shaft, wheel and key in operative position with relation to each other, and comprising a pair of fixedly spaced side members adapted to straddle said key and engage said shaft and wheel and having slots formed therein to receive a key-drift, and a key-drift adapted to engage said slots and the head of said key, the distance between the shaft engaging inner edge of each member and the adjacent inner edge of the slot in said member being greater than the exposed thickness of said key where inserted in said shaft.

8. In a key removing device, a holder for the key-drift comprising a pair of side members and a spacing bridge connecting the corresponding edges thereof, said bridge being shorter than said side members, and said side members having apertures formed therein adjacent said bridge and substantially in alinement with each other, said side

members having the inner portion of their edges chamfered from said bridge to one end thereof.

9. A key removing device adapted to be used in conjunction with a shaft, wheel and key in operative position with relation to each other, and comprising a pair of side members and a spacing bridge raised a distance above the connected portions of said side members, said side members being adapted to straddle said key and engage said shaft and wheel and having slots formed therein to receive a key-drift, and a key-drift adapted to engage said slots and the head of said key, the distance between the inner surface of said bridge and the adjacent inner edges of said slots, and between the shaft-engaging inner edges of said members and the adjacent inner edges of said slots, being greater than the exposed thickness of the body portion of said key.

In testimony whereof I have hereunto affixed my signature this 27th day of June, 1918.

ROY F. WHALLEY.
